ATTORNEYS.

UNITED STATES PATENT OFFICE.

WILLIAM A. RINGLER, OF PHILADELPHIA, PENNSYLVANIA, ASSIGNOR TO GLOBE
WERNICKE CO., OF CINCINNATI, OHIO, A CORPORATION OF OHIO.

ARTICLE FILE.

Application filed October 10, 1922. Serial No. 593,546.

To all whom it may concern:

Be it known that I, WILLIAM A. RINGLER, a citizen of the United States, residing at Philadelphia, county of Philadelphia, State 5 of Pennsylvania, have invented a new and useful Article File, of which the following is a specification.

My present invention comprehends a 10 novel construction of an article file which is adapted to be employed in filing or sorting a large variety of articles such as, for example, bank checks, cards or other papers.

It further comprehends a novel construction of an expandible frame, a novel construction of a follower block and novel means for locking the follower blocks in their adjusted position.

Other novel features of construction and advantage will hereinafter appear in the 20 detailed description and the appended claims.

For the purpose of illustrating my invention, I have shown in the accompanying drawings a typical embodiment thereof 25 which is at present preferred by me, since this embodiment will be found in practice to give satisfactory and reliable results. It is, however, to be understood that the various instrumentalities of which my invention 30 consists can be variously arranged and organized and that my invention is not limited to the precise arrangement and organization of these instrumentalities as herein shown and described.

Figure 1 represents, in end elevation, an 35 article file, embodying my invention.

Figure 2 represents a side elevation of my device.

Figure 3 represents a section on line 3—3 40 of Figure 1.

Figure 4 represents on a reduced scale a front elevation of the lower end of one of the cards.

Figure 5 is a detail longitudinal section 45 on the line of one of the tubular rods.

Similar numerals of reference indicate corresponding parts.

Referring to the drawings,

The frame is adapted to be expanded or 50 contracted as may be desired, and is formed of two sections, which are counterparts of each other. The frame is provided with end bars 1 and 2, respectively, 3 designates tubular rods spaced from each other and connected at one end to the end bar 1. In a

similar manner, tubular spaced rods 4 are connected at one end to the bar 2. These rods 3 telescope into the rods 4. The end bar 1 has fixed to it one end of a plate 5 which is slidable upon a similar plate 6 secured at one end to the end bar 2. The plate 5 has at the sides the downwardly and inwardly directed flanges 7 forming a channel to receive the plate 6, and the flanges 7 are deflected, as at 8, to form a stop for the 60 clamping plate 9, through which passes a threaded rod 10 fixed to the plate 6 and provided with a clamping nut 11. The cards 12 are apertured to be received on the rods 3, and are provided with index tabs 70 13. 14 designates the front follower block, and 15 the rear follower block, each of which is of the same construction and locked in place by means of similar locking mechanism. The follower blocks are apertured to 75 receive the rods 3. Each follower block has pivoted to it, at 16, a manually actuated locking member 17 in the form of a lever having at one end the laterally extending cam 18 and the wedge-shaped tongues 19.

The lever 17 co-operates with a locking member 20 of novel construction. The member 20 is preferably formed from a metal rod having its ends joined together and provided with a laterally extending top 21 which merges into the sides 22, which latter, at their lower ends, form the loops or U-shaped portions 23 which merge into the laterally extending bottom 24. The sides 22 are freely slidable in the guides 25 secured 90 to their respective follower block. 26 designates a name-plate holder fixed to a follower block. 27 designates cushions, illustrated in the form of rubber bands surrounding the ends of the end bars 1 and 2 of the frame.

The operation of my novel article file will now be readily apparent to those skilled in this art, and is as follows:

The frame can be expanded to increase its capacity by loosening the thumb nut 11 100 and moving the end bar 2 away from the end bar 1, the thumb nut 11 being then tightened when the desired expansion has been attained. The frame can be contracted by moving the end bars 1 and 2 toward each 105 other. When it is desired to use the article file, the rear or front follower block, or both, can be unlocked by raising upwardly the lever 17, thereby releasing the locking member 20. When the locking lever 17 is moved 110

into its locked position, it will be apparent that the cam 18 will press downwardly on the laterally extending top 21, the wedge-shaped tongues 19 passing between such top 21 and its follower block 14. This positively locks the plates in position since the cam 18 presses and holds down the top 21 of the locking member, and the wedge-shaped tongue 19 wedges between the follower block 14 and the top member 15 so that the sides 22, see Figure 1, are in frictional engagement with the guides 25 carried by the follower block. In this manner the loops 23 will be clamped against the tubular rods 3 so that the follower block will be rigidly clamped with respect to the frame, and when both follower blocks are in clamped position, the cards or articles between them will be securely held in place. It will be apparent that the cards 20 and follower block are cut out so that they are slidably mounted on the upper plate 5, see Figure 3.

The follower blocks act as compression blocks to secure the articles in place in the file, and either one or both of the follower blocks may be in locked position. If both are in locked position, compression is obtained at the upper portions of the articles. When the resilient rods 20 move downwardly into clamped position, they are clamped against the tubular rods 3 as well as against the guides on the upper plate 5, and since the rods 3 pass through the follower blocks a very effective resilient clamping action is obtained, and since the transversely extending portions 24 of the clamping members are, so to speak, offset a very strong compressing action is also obtained as the tendency of the follower block is to move longitudinally 40 of the frame in a direction away from the point at which it is clamped.

It will now be apparent that I have devised a novel and useful article file which embodies the features of advantage enumerated as desirable in the statement of the invention and the above description, and while I have, in the present instance, shown and described an embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:

1. An article file having an expandible and contractible frame with means to secure it in its adjusted position, follower blocks carried by said frame and adjustable thereon, a locking member slidably carried by each follower block to clamp against said frame, and means on the follower block to actuate its locking member.

2. An article file, comprising an expandible and contractible frame formed of sections provided with a plurality of telescoping rods and a pair of overlapping plates, means to lock said plates together to secure 70 said frame sections in their adjusted position, follower blocks carried by said frame and longitudinally and angularly adjustable thereon, and locking mechanism for said follower blocks to cause a greater compression 75 on the upper portions of the articles between said follower blocks than on the lower portion of the articles.

3. An article file, comprising an expandible and contractible frame formed of sections provided with a plurality of telescoping rods and a pair of overlapping plates, means to lock said plates together to secure 80 said frame sections in their adjusted position, one of said plates having means to prevent complete separation of said sections, follower blocks movably carried by said frame, and locking mechanism for said follower blocks to cause a greater compression 85 on the upper portions of the articles between 90 said follower blocks than on the lower portions of the articles.

4. In an article file, a frame, follower blocks movably carried by said frame and locking mechanism for said follower blocks, said locking mechanism comprising a resilient member slidably mounted on its follower block for bodily vertical movement thereon, and a second member movably carried by said follower block and having means to engage said resilient member to effect its locking engagement with said frame.

5. In an article file, a frame having end members, and spaced members connecting them, follower blocks slidable on said frame, and locking mechanism for said follower blocks comprising a resilient locking member having portions to overhang said members and having a resilient top portion, said locking member being slidably carried by its follower block, and a second locking member to engage said resilient top portion to compress said overhanging portion against said spaced members.

6. In an article file, an expandible and contractible frame, comprising end members, a pair of spaced rods extending from each member, the rods of one member having telescoping relationship with the rods of the other member, a plate carried by each member, one of said plates overhanging the other, means to lock said plates in their adjusted position and thereby determine the capacity 120 of said file, follower blocks slidably mounted on said frame, spring locking members carried by said follower blocks and slidable thereon and having portions extended to engage said frame and clamp the follower blocks in position, and means carried by 125 130

said follower blocks to actuate said spring locking members.

7. In an article file, a frame, a follower block movable thereon, and locking mechanism for said follower block, comprising a resilient member movably carried by the follower block to clamp against said frame, and a lever carried by said follower block and adapted to engage said resilient member to move it into and retain it in its locked position, said lever having a tongue to move said member away from its follower block and a cam to cause the locking movement of said member.
- 10 8. In an article file, a frame having side and intermediate supporting members, a follower block movable on said supporting members, and locking mechanism for said follower block comprising a resilient locking member extending transversely across said supporting members provided with upwardly extending portions movably carried by
- 15
- 20

said follower block, and also provided with a top portion, and manually actuated means engaging said top portion to move said resilient locking member into locking engagement with said side and intermediate members.

- 25 9. In an article file, an expandable and contractible frame having end bars, and telescoping rods and overlapping plates connecting them, a follower block apertured to be received on said rods, cards apertured to be received on said rods, a locking member having its lower portion offset and deflected to overhang said rods, slidably carried by said follower block and having an upper resilient portion, and a manually actuated member carried by said follower block and adapted to engage said resilient portion to 30 force the deflected lower portion of the locking member against said rods.
